UNITED STATES PATENT OFFICE.

FREDERICK HUGH SMITH, OF DATCHET, ENGLAND.

GOVERNOR FOR INTERNAL-COMBUSTION ENGINES.

No. 838,754.

Specification of Letters Patent.

Patented Dec. 18, 1906.

Application filed May 12, 1905. Serial No. 260,122.

To all whom it may concern:

Be it known that I, FREDERICK HUGH SMITH, a subject of the King of Great Britain and Ireland, residing at Home Works, 5 Datchet, in the county of Buckingham, England, have invented certain new and useful Improvements in and Relating to Governors for Internal-Combustion Engines, of which the following is a specification.

10 This invention relates to governors for internal-combustion engines of the type in which the increased suction from the carbureter, due to an increased speed of the engine, operates a valve which controls the charge 15 drawn into the engine-cylinder.

Governors of this type, generally called the "induction" type, have hitherto been known in which a valve is operated by the engine suction.

20 Now the object of the present invention is to provide simple and compact means for controlling the valve by hand or other suitable means without interfering with its automatic action.

25 The present invention consists in a governor of this type in which the valve is directly operated by the engine suction against the action of a spring and is supported in a movable carriage, so that it may be moved with 30 its controlling-spring nearer to or farther away from its closing position without altering the tension of said spring.

Referring now to the accompanying drawings, which form part of my specification, 35 Figure 1 is a vertical section through the engine induction-pipe, showing the arrangement of my governor within that pipe. Fig. 2 is a vertical section at right angles to the section shown in Fig. 1.

40 In carrying the invention into effect according to one form, as illustrated in the accompanying drawings, a spring-controlled puppet-valve *a* is placed in induction-pipe *b*. The valve *a* is guided by its central rod *c*, leading to the engine-cylinder *w*, in a carriage *d*, to which are fixed arms *e* and *f*. These arms extend through sloping slots *g* and *h* in the walls of the induction-pipe, and also through vertical slots *j* and *k* in a sleeve *m*, 45 adapted to work outside the induction-pipe *b* and under the control of a hand-lever *n*. The carrying-block *d* is provided with a collar *p*, against which, on its under side, there bears the spring *o*, while on the top side the spring *r* rests. The spring *o* also bears on the valve *a*, which is preferably dished, as shown, while

the spring *r* bears on a loose collar or washer *s* on the head of the guide-spindle *c*, this loose collar being adjusted by means of nuts *t*.

The action of this device is as follows: Under ordinary circumstances the springs *o* and *r* coact to hold the valve *a* open the desired amount, this amount being determined by the hand controlling-lever *n*. Thus if the slanting slots *g* and *h* are right-handed, as 60 shown in Fig. 1, by rotating the lever *n* in a clockwise direction the maximum amount of opening is obtained. Similarly by moving the lever in a counter-clockwise direction the block *d* is carried upward and the amount of 65 opening of the valve *a* is reduced. This relates to the hand control.

The automatic governing action is as follows: Assume that the lever *n* has placed the valve in its mean position. When the charge 75 is being sucked into the engine-cylinder through the pipe *k* in the direction shown by the arrow *x*, the valve *a* is drawn toward its seating. Under normal working the springs *o* and *r* maintain the valve *a* open in spite of 80 this suction. When the engine speed increases, the suction increases, and consequently the valve *a* throttles the charge. The valve *a* does not, however, operate till the engine-piston has very nearly reached its mid- 85 position, when, as is well understood, its speed is maximum, and consequently the suction is greatest. The balancing of the spring *o* and *r* is such that when the engine speed goes above certain limits the valve *a* closes. Fur- 90 ther, it will be seen that when valve *a* has once closed it will remain closed during the remainder of the charging stroke, because of the increased suction due to the continued outward motion of the engine-piston. In 95 this way the governing is rendered very sensitive, because whenever the valve *a* commences to throttle it will invariably close completely, since as the valve *a* approaches toward its seating the suction force on the 100 valve *a* is increased by the combined action of the throttled suction-passage and the increased engine speed.

Other forms of valve may be used for throttling the charge—as, for instance, a piston-valve having ports. The form described, however, is that which in practice I prefer to employ, because of its cheapness and easy manufacture, and also because it provides a very efficient governor of the induction type. 105 It will be seen that with this invention the engine may be conveniently controlled au- 110

tomatically and by hand with the same valve.

Having thus described my invention, what I claim as new, and desire to secure by Letters Patent, is—

1. A governor for internal-combustion motors having in combination on the engine induction-pipe, a spring-controlled valve arranged to open and close in the direction of the engine suction, and means connected with the valve for moving the valve in that direction by hand without altering the tension of the spring, substantially as described.

2. A governor of the induction type for internal-combustion engines, having in combination a spring-controlled valve interposed in the path of the fluid flowing into the engine-cylinder, a valve-stem; a carriage *d*, engaging said valve-stem and supporting said spring-controlled valve, and means connected with the carriage for moving the carriage with the valve and spring in the direction of opening and closing of said valve without altering the tension of the spring substantially as described.

3. A governor of the induction type for internal-combustion engines, having in combination, a dished valve *a*; a valve-stem, springs *o* and *r* controlling said valve; a carriage engaging said valve-stem and supporting said valve and springs and means connected with the carriage for moving said carriage with

the valve and spring in the direction of opening and closing of said valve, substantially as described.

35

4. In combination with an internal-combustion engine, a governor of the induction type, comprising a spring-controlled valve in the engine suction-pipe a carriage *d* supporting said spring-controlled valve; slanting slots in the walls of said suction-pipe; arms extending from the carriage *d* and guided in said slanting slots; and means for moving said arms in the slots, substantially as and for the purpose described.

45

5. In combination with an internal-combustion engine, a governor of the induction type comprising a valve *a* located in the engine suction-pipe; controlling-springs *o* and *r*; a carriage *d*; arms *e* and *f* extending from said carriage; slots *g* and *h* formed in the walls of the engine suction-pipe and adapted to guide the arms *e* and *f*; a sleeve *m* surrounding the engine induction-pipe and receiving the ends of the arms *e* and *f*; a lever *n* for rotating said sleeve, substantially as described.

50

In testimony whereof I have signed my name to this specification in the presence of two subscribing witnesses.

FREDERICK HUGH SMITH.
